Des. 178,697
Patented Sept. 4, 1956

178,697

COMBINED MEAT CLEAVER, TENDERIZER, CAN AND BOTTLE OPENER

Paul Rossi, Warren, Ohio

Application July 1, 1955, Serial No. 36,795

Term of patent 14 years

(Cl. D11—1)

FIG. 1.

FIG. 3.

FIG. 2.

FIG. 4.

Figure 1 is a side elevational view of a combined meat cleaver, tenderizer, can and bottle opener showing my new design;

Figure 2 is a bottom plan view thereof showing the cutting edge of the blade;

Figure 3 is an end elevational view thereof looking from the right of Figure 1; and

Figure 4 is a side elevational view opposite to that of Figure 1.

I claim:

The ornamental design for a combined meat cleaver, tenderizer, can and bottle opener, substantially as shown.
